UNITED STATES PATENT OFFICE.

ISAAC LITNER, OF BROOKLYN, NEW YORK.

REFLECTOR.

Application filed May 3, 1922. Serial No. 558,082.

To all whom it may concern:

Be it known that I, ISAAC LITNER, a citizen of the United States, and a resident of the city of New York, borough of Brooklyn, 5 in the county of Kings and State of New York, have invented a new and Improved Reflector, of which the following is a full, clear, and exact description.

This invention relates to reflectors, and 10 particularly to an improved reflector capable of receiving a globe as well as an ordinary electric lamp.

The object of the invention is to provide a simple effective construction which will 15 properly diffuse light, and which may readily receive a globe as well as the ordinary electric lamp or bulb.

Another object of the invention is that of 20 providing a reflector having more than one reflecting surface, one surface intended to reflect the light emitted by the bulb and the other to reflect the light emitted by the globe which receives the reflected light of the bulb.

25 In the accompanying drawings:—

Figure 1 is a vertical sectional view through a reflector disclosing an embodiment of the invention; and

30 Figure 2 is an inverted plan view of the reflector shown in Figure 1.

Referring to the accompanying drawings by numeral, 1 indicates a hood which may have any suitable ornamental appearance, and which is provided with an annular lower 35 end section 2 carrying suitable globe supporting screws 3, whereby a globe 4 may be properly supported.

Associated with the hood 1 is a lower reflector 5 and also an upper reflector 6. The 40 lower reflector 5 is provided with an annular frusto-conical shaped metallic member 7 provided preferably with a bead 8, which bead is soldered or otherwise rigidly secured to the annular member 2. The lower 45 edge of the member 7 is provided with a straddling U-shaped member 9, preferably of metal which is also preferably soldered to the body or member 7 and presents an inwardly extending flange 10 designed to receive one end of the various reflecting 50 glasses 11. These glasses may be plain mirrors, or may be corrugated as preferred. As indicated in Figure 2 each of the mirrors 11 tapers from the outer end to the inner end, said inner end being held in place 55 by a plurality of fingers 12 bent to a proper

position, said fingers being preferably integral with the annular band or ring 13, which annular band or ring is soldered or otherwise rigidly secured to the annular 60 end section 2. The opposite edge of the band 13 to that carrying the fingers 12 is provided with a comparatively few fingers 14, there being only three shown in the drawing, but a greater or less number might 65 be used if desired. The fingers 14 act as retaining fingers for retaining the reflector 6 in position. This reflector is of a size to bear against the hood 1 and be supported at the lower end of the fingers 14. This reflector is 70 provided with a body or frusto-conical shaped plate 15 having a turned-over edge 16 at the upper end for holding the upper ends of the reflecting mirrors 17 in place while the lower ends are held in place by a flange 18 extending inwardly from the U-shaped straddling member 19. The straddling member is preferably soldered or otherwise rigidly secured to the body or plate 15. The 75 hood 1 is provided with a suitable clamping member 20 for clamping the hood to an electric bulb socket and to adjustably position the bulb at a proper point beyond the reflector. It will be noted that by providing the inner reflector 6, substantially all 80 of the light is reflected or thrown out and when the globe 4 is used, is directed into said globe and downwardly or against the reflector 5 and from thence reflected according to the angle of the mirrors 11. The 85 construction in the accompanying drawing not only provides a proper reflector in connection with globe 4, but provides an inner reflector 6 to insure the proper reflection of most of the light rays and the consequent 90 direction of the light rays to the desired field to be illuminated.

I claim:

1. A reflector of the character described, comprising a casing having an annular end section, an annular reflecting member secured to said end section, a ring secured to said end section provided with upper and lower sets of fingers, said annular reflecting member having a plurality of separate mirrors arranged therein engaging the lower set of fingers, whereby said fingers assist in retaining said mirrors in place, and an inner annular reflecting surface engaging the other of said fingers so as to be held in place 100 thereby.

2. A reflector of the character described,

comprising a casing having an annular end section, an annular reflecting member secured to said end section and provided with a plurality of removable mirrors, a ring secured to said end section having fingers overlapping said mirrors and retaining the same in place, said ring having an upper set of fingers, an annular reflecting member arranged in said casing and supported by said 10 second set of fingers.

3. In a device of the class described, a

ring having a plurality of fingers at both edges thereof, a cover extending radially inward secured to the upper edge of said ring, a cover extending radially outward also secured to said ring at its lower edge, means extending through said ring for holding in place a globe, and reflecting surfaces below the upper cover and the lower cover held in place by said fingers for reflecting light into 20 the globe and from the globe.

ISAAC LITNER.
